UNITED STATES PATENT OFFICE

1,936,824

METHOD OF MAKING METALLIC RAILWAY SLEEPERS

Theodor Buchholz, Berlin-Dahlem, Germany, assignor to American G E O Company, New York, N. Y.

Application August 21, 1929, Serial No. 387,448, and in Germany November 20, 1928. Renewed September 27, 1933

14 Claims. (Cl. 29—169)

It has hitherto not been possible to roll railway ties or sleepers having rail guiding ribs longitudinally, owing to the ribs being too high, as it is impossible to run a bar having a repeatedly varying cross section several times through the passes. The separate recurring projections would otherwise not coincide with the grooves in the rolls.

According to the present invention the railway ties or sleepers are to be cogged down in long bars longitudinally, in the first instance only with cogged down projections. From these bars separate pieces are cut off and these pieces are thereupon further treated in a special manner, for instance in rolls having suitable grooves for the ribs. Such short lengths, with only two changes of cross-section, even when run through repeatedly can adapt themselves well to the passes of grooved rolls. The constrictions in the section produced in rolling section bars having a varying cross section are equalized when finish-rolling or forging the sleeper.

The requisite ribs may alternatively be formed from the rough-rolled swells or projections by upsetting the cross section of the sleeper; or enlargements formed by upsetting may be reduced to the desired rib shape by pressing or the like. Simultaneously with the finish-pressing of the ribs the recesses to be formed in them may be completely or partially rough-pressed.

The undercut recesses may also be formed by drifting or by milling.

For the purpose of prolonging the life of the sleeper, the top of the sleeper may be reinforced at and in the vicinity of the rail seat.

The method according to the invention is illustrated in the accompanying drawings, in which

Fig. 1 is a cross section on the line I—I in Fig. 2, through a rolled bar with cogged down swells; and

Fig. 2 is a longitudinal section through the rolled bar.

Fig. 3 shows in cross section on the line III—III in Fig. 4, and

Fig. 4 shows in longitudinal section a sleeper length cut off from the rolled bar shown in Figs. 1 and 2, ready for further rolling in the grooved rolls.

Fig. 5 is a cross section through the finished rail tie or sleeper on the line V—V in Fig. 6, and Figs. 6 and 7 show in longitudinal section and in plan view respectively the finished shape of the sleeper, with inclined rail seats produced by pressing or drop forging.

Fig. 8 shows a cross section on the line

VIII—VIII in Figure 9, through a rolled bar with rough rolled thickenings at the rail seats, and

Fig. 9 shows a longitudinal section of the rolled bar;

Fig. 10 shows a cross section on the line X—X in Figure 11, and

Fig. 11 shows a longitudinal section through about half a sleeper, after the pressing of the rail support but before the upsetting of the rail-guiding ribs, and sections through the pressing and upsetting implements;

Fig. 12 shows a cross section on the line XII—XII in Figure 13, and

Fig. 13 shows a longitudinal section through about half a sleeper after the upsetting of the ribs, and also sections of the pressing and upsetting tools;

Fig. 14 shows a cross section on the line XIV—XIV in Figure 15, and

Fig. 15 shows a longitudinal section through about half a finished sleeper, after the ribs have received their final shape by after-pressing or the like, and also a section of the requisite tool.

Fig. 16 shows in plan view a railway sleeper with rail guide ribs formed by drop forging the swells in a die,

Fig. 17 shows a cross section on the line XVII—XVII in Fig. 16, and

Fig. 18 shows a cross section on the line XVIII—XVIII in Fig. 16.

Fig. 19 is a cross section through a sleeper on line XIX—XIX in Fig. 21, showing a recess ready to be opened by drifting,

Fig. 20 shows the same cross-section after the drifting operation,

Fig. 21 is a longitudinal section through the sleeper shown in Figs. 19 and 20 at the rail seat,

Fig. 22 is a perspective view of the drift employed, and

Fig. 23 is a perspective view showing the die alone inverted.

Fig. 24 is a cross section, on the line XXIV—XXIV in Fig. 25, of a sleeper with bridge-pieces rolled on its under side,

Fig. 25 is a longitudinal section of the sleeper shown in Fig. 24 at the rail seat, and

Fig. 26 shows a modified constructional form of this sleeper in longitudinal section at the rail seat.

Figure 27 shows part of a sleeper in longitudinal section, with one guide rib in an unfinished state and the other finished.

The long bar shown in Figures 1 and 2 has been longitudinally rolled to the approximate section of a railway tie or sleeper, with laterally extend-

85

100

105

110

ing projections or swells *a* on the upper side. This bar is then cut up into lengths, each corresponding to one sleeper, these sleeper lengths are further rolled out in grooved rolls to a form such as 5 that shown in Figures 3 and 4. When suitable grooves are provided part of the swell that is to form the rail seat can be cogged down, pressed or drop forged with an inclination, as indicated by broken lines in the swells *a* in Fig. 4. In the 10 middle of the longitudinal section is a thickening *b*, which serves to provide material for the purpose of making up differences in the gauge when the sleeper is being finish-pressed. The rolled ribs are then given their final shape, and the 15 rail seats are given the required inclination, by pressing or drop forging in a die, and at the same time the ties are capped at their ends, thus producing the finished railway tie shown in Figures 5, 6 and 7, where *h*, *h* are the rail guides, 20 and *j*, *j* the rail seats.

Figures 8 to 15 illustrate a method in which the thickened portions *a* are partially shaped by an upsetting operation.

According to Figures 8 and 9 the rolled profile 25 of the sleeper receives at the rail support and in the neighbourhood thereof circumferential rough rolled reinforcements *a*. In the middle of the sleeper a swell *b* is again provided, which, after the sleepers have shrunk upon cooling below the 30 gauge, is pressed down to a greater or less extent.

From the rolled bars pieces of about the length of a sleeper are cut off, as illustrated in Fig. 9. The parts to be upset are thereupon warmed and then clamped between press tools *i* and *i*, and 35 simultaneously or previously or subsequently the upsetting jaws *d*, *d* and *e*, *e* are mounted, as shown in Figs. 10 and 11, and these are then moved in the direction of the arrows in Fig. 11 towards the press tools *i*, *i*, until they reach the 40 position shown in Figure 13, so that the swells *f* are formed. The swells *f* are then shaped to the desired ribs in a press tool *g*, *g*, as shown in Figs. 14 and 15. The excess material of the swells may be utilized, by suitable recesses in the under portion 45 of the press tool, for swell-like thickenings *k* located underneath the top of the sleeper.

In the press tool illustrated in Figure 14 the recesses *c* may be pressed in simultaneously with the finish-pressing of the ribs. This not only 50 considerably reduces the work of milling, but the material to be displaced by pressing assists in increasing the height of the ribs. The increases in the cross section formed by cogging down are intended to remain, insofar as they are not upset, 55 in order that the sleeper shall be reinforced just at the rail seat so as to be capable of withstanding the stresses at these places.

By suitably constructing the press tool according to Figure 15 the capping (or adzing) and recessing of the sleepers may be effected simultaneously with the finish-pressing of the ribs. By this recessing or notching the sleeper receives 60 on the rail seat the prescribed inclination for the rail.

65 The sleeper shown in Figures 16, 17 and 18 is made from a rolled bar provided with swells. The rail guide ribs *h* are formed by drop forging the swells in the die.

When the ribs are formed by drop forging in a 70 die instead of being rolled from the cogged down swells, the material is not distributed, as is the case when rolling, in the longitudinal direction of the sleepers, but in the lateral parts of the cross section of the sleeper, more particularly the 75 roof-shaped parts, as shown in Figure 17. This

has the advantage that the cross section of the sleeper will be reinforced just at the rail seat and in the vicinity thereof, so that the known detrimental springing apart of the cross section of the rail seat is prevented, or at least reduced.

The main advantage provided by drop forging the swells in a die is that those parts of the swells from which the ribs are formed will come to the top during forging, so that the cogged down swells need not be of the height which the forged ribs must have. It is thus possible for the swells of the rolled bars to be made lower, which considerably facilitates the rolling operation.

The swells may also be cogged down with or without grooves; in the latter case the grooves are formed when the swells are being drop forged in the die, in order to facilitate the milling out of the undercut recesses of the ribs.

By drop forging the sleepers in the die, greater accuracy is obtained in the distance of the ribs from one another than by rolling. Any slight differences in gauge still remaining may be equalized by drawing down or upsetting the cross section of the sleeper, the latter being effected in either the hot or the cold state.

The sleeper may also be widened at the rail seat over the whole cross-section by drop forging in the die, as shown in the right hand part of Fig. 16 and in Fig. 20. By this means the hollow space in the sleeper is widened so as to be capable 100 of receiving a greater amount of ballast. This widening at the rail seat gives the sleeper a greater resistance to wear due to the rail foot. This widening is of particular advantage when 105 elastic intermediate plates are used between the rail foot and the top of the sleeper, as the elastic intermediate plates will have a longer life when the rail seat is wider and as the frictional resistance will be greater. In the case of railways using both wood and iron sleepers it is of particular advantage to be able to adapt the widening of the rail seat surface of the iron sleepers to the width of the sole plate for wooden sleepers, so that poplar wood plates of the same width can 110 be made for both rail seats.

Figures 19 to 23 illustrate the opening of the recess *c* in the rail guides by drifting.

Before drifting, the die *m*, shown upside down in Fig. 23, is placed between the guide ribs *h*, as shown in Figure 21. The die *m* has a longitudinal groove *q* in its under side, into which the drift *n* is driven. The drift *n*, as shown in Figure 22, comprises a core part *o*, the cross section of which corresponds to the original cross section of the recess *c*, as shown in Figure 19, 130 and lateral projections *p*, which correspond at the rear end to the profile of the finished recess *c* shown in Figure 20, but taper away towards the forward end of the drift, terminating in sharp 135 points beside the lower edges of the core piece *o*, preferably at a certain distance from the forward end of the drift.

The die may if desired consist of two or more parts; or in place of a single drift several drifts 140 may be used.

The recesses in the ribs of sole plates can of course be made in the same way.

Producing the recesses by drifting is cheaper than milling, and makes the material denser, and 145 also provides the possibility of the cogged down swells being made of less height, as the drift forces the material of the undercut places upwards. The height of the cogged down swells need thus only be such that the correct height 150

can be obtained by one passage of the material through the milled rolls.

In the case of the rail ties illustrated in Figures 24, 25 and 26, in order that the material of the 5 rolled swells *a* lying between the ribs shall not become too wide when being pressed down at the rail seat, the matrix is provided with one or two slots, into which the excess material is forced. The material provided by the rolled swells is thus 10 utilized not only for forming the rail guide ribs *h* but also for forming transverse bridge-pieces or longitudinal ribs on the under side of the top of the rail tie. Figures 24 and 25 shown in full lines a transverse bridge *s* midway between 15 the guiding ribs *h*, and in broken lines a longitudinal rib *t* in the middle of the tie. Figure 26 shows two transverse bridges *u*, spaced wider apart than the rail guides *h*. In this case a swell *v* is preferably provided below the rail seat, to 20 enable the ballast to distribute itself better and to force it together. The ribs *u* prevent the ballast escaping laterally under the working pressure. These bridge-like swells also have the 25 advantage that the cross section of the sleeper is re-inforced just at the laces which are subjected to the greatest stresses. When the bridge extends at right angles to the cross-section of the sleeper it provides the further advantage of greater security against lateral displacement 30 of the sleeper in the ballast.

Instead of forming bridges, the excess material may be forced downwards to form other projections between or behind the ribs. When the sleepers are laid on previously formed ballast 35 boxing, such projections have a beneficial effect on the density of the ballast, this being of particular advantage underneath the rail seat.

Instead of the guide ribs being provided with recesses for the lateral insertion of the heads of 40 the clip screws, they may be undercut longitudinally, wedges being inserted for gripping the rail foot, as shown in Fig. 27, where *x* represents a left hand guide rib in the unfinished state, and *y* the right hand finished undercut guide rib, 45 with the wedge *z* driven in. The undercut recesses in the guide ribs may be parallel or may be inclined to one another.

It has already been proposed to fit rails with such wedges, but in such cases the requisite 50 undercuts of the guiding ribs are formed by punching out jaws from the top of the sleeper or by welding on supporting plates with rolled on guiding ribs. The former method of manufacturing has the disadvantage that the cross section of the sleeper is considerably weakened just at the most vital part, and the latter method has the disadvantage that several supporting plates must be made and that these have to be welded or riveted to the sleepers in a known inconvenient and costly manner. The two methods of fixing have in common the further disadvantage that they are liable to be damaged through the wedges being frequently hammered in.

60 According to the invention all these disadvantages are overcome by the solid ribs which are formed from the cogged up or upset swells being undercut for receiving the wedges by milling, driving in a flat drift, bending over or the like. As the ribs formed in this way extend right into the roof-shaped inclined parts of the 70 sleeper section, the wedge surfaces are lengthened, so that the wedges will have a better grip.

What I claim is:

75 1. A method of manufacturing iron railway

sleepers with guide ribs for the rails, comprising first longitudinally rolling long iron bars to the approximate section of the sleeper with laterally extending projections or swells on the upper side, and thereupon forming the said swells into the guide ribs for the rails, as and for the purpose set forth. 80

2. A method of manufacturing iron railway sleepers with guide ribs for the rails, comprising first longitudinally rolling long iron bars to the approximate section of the sleeper with laterally extending projections or swells on the upper side, and then by longitudinal rolling forming the said swells into the guide ribs for the rails, as and for the purpose set forth. 85

3. A method of manufacturing iron railway sleepers with guide ribs for the rails, comprising first longitudinally rolling long iron bars to the approximate section of the sleeper with laterally extending projections or swells on the upper side and then forming the said swells into the guide ribs for the rails and into the rail seat, as and for the purpose set forth. 90

4. A method of manufacturing iron railway sleepers with guide ribs for the rails, consisting in 100 rolling a long bar longitudinally to the approximate section of the sleeper with laterally extending projections or swells on the upper side, cutting lengths from the said rolled bar and forming the said swells into the guide ribs by passing the said lengths longitudinally through rolls provided with suitable grooves, as and for the purpose set forth. 105

5. A method of manufacturing iron railway sleepers with guide ribs for the rails, consisting 110 in rolling a long bar longitudinally to the approximate section of the sleeper with projections or swells on it, cutting lengths from the said rolled bar and forming the said swells into the guide ribs by passing the said lengths longitudinally through rolls, giving the rolled ribs their final shape by pressing or drop forging in a die and at the same time capping the sleepers at their ends, as and for the purpose set forth. 115

6. A method of manufacturing iron railway 120 sleepers with guide ribs for the rails, consisting in forming by longitudinally rolling a long iron bar to the approximate section of the sleeper with projections or swells on it, forming the said swells into the guide ribs for the rails and into 125 the rail seat, and giving the rail seats the required inclination by pressing or drop forging in a die, as and for the purpose set forth.

7. A method of manufacturing iron railway 130 sleepers with guide ribs for the rails, consisting in forming transverse thickened parts by upsetting the sleeper and in thereupon giving the said parts the required rib shape by pressing, as and for the purpose set forth.

8. A method as claimed in claim 7, and comprising the step of rolling the sleeper with reinforcements at the rail seat and in its vicinity for facilitating the upsetting operation, as and for the purpose set forth. 135

9. A method of manufacturing iron railway 140 sleepers, consisting in forming swells in the material of the sleeper and forming the swells into rail seats and guide ribs for the rails by drop forging the swells in dies, as and for the purpose set forth. 145

10. A method as claimed in claim 9 and comprising the step of widening the sleeper at and in the vicinity of the rail seat by drop forging the swells in dies, as and for the purpose set forth. 150

11. A method of manufacturing iron railway

sleepers, consisting in forming swells in the material of the sleeper and by drop forging in dies forming the swells into rail seats and guide ribs and grooves in the ribs and milling out the 5 grooves to form undercut recesses in the ribs, as and for the purpose set forth.

12. A method of producing undercut recesses for the heads of the clip bolts in the ribs of iron railway sleepers, consisting in forming grooves in 10 the said ribs by pressure and in opening out the said recesses by drifting to form the undercutting, as and for the purpose set forth.

13. A method of manufacturing iron railway sleepers with rail seats consisting in forming 15

swells on the top part of the sleeper and by pressing forming the said swells into guide ribs for the rails on the top surface of the sleeper and into swell or bridge-like reinforcements on the under side of the sleeper in the vicinity of the 80 rail seats, as and for the purpose set forth.

14. A method of manufacturing iron railway sleepers with guide ribs for the rails, comprising forming swells in the material of the sleepers, converting the swells into guide ribs by pressure 85 and longitudinally undercutting recesses therein for the insertion of wedges for fixing the rail foot.
